CLAIM

The ornamental design for a carton, as shown and described.

DESCRIPTION

FIG. 1 is a perspective view of a carton showing my new design, in a closed configuration.

FIG. 2 is a left elevation view of the carton of FIG. 1, the right elevation view is a mirror image.

FIG. 3 is a front elevation view of the carton of FIG. 1.

FIG. 4 is a rear elevation view of the carton of FIG. 1.

FIG. 5 is a top plan view of the carton of FIG. 1.

FIG. 6 is a bottom plan view of the carton of FIG. 1.

FIG. 7 is a top plan view of the carton of FIG. 1 in an open configuration; and,

FIG. 8 is a plan view of the carton of FIG. 1 shown in an unfolded configuration.

All evenly-spaced broken lines shown in the drawings are for the purpose of illustrating parts of the article that form no part of the claim.

1 Claim, 8 Drawing Sheets
